By Attorney Francis A. Parker,

UNITED STATES PATENT OFFICE.

WILLIAM S. MACHARG, OF CHICAGO, ILLINOIS, ASSIGNOR TO THE LUXFER PRISM PATENTS COMPANY, OF SAME PLACE.

TILE WITH PARTIALLY-REMOVED CORNERS.

SPECIFICATION forming part of Letters Patent No. 595,269, dated December 7, 1897.

Application filed August 23, 1897. Serial No. 649,213. (No model.)

To all whom it may concern:

Be it known that I, WILLIAM S. MACHARG, a citizen of the United States, residing at Chicago, in the county of Cook and State of Illinois, have invented certain new and useful Improvements in Tile with Partially - Removed Corners, of which the following is a specification.

My invention relates to a new and improved prism-light with its corners partially removed.

My invention is illustrated in the accompanying drawings, wherein—

Figure 1 is a plan view of a single prism-light of my invention. Fig. 2 is a perspective view of one corner; and Fig. 3, a plan view of a portion of a plate, showing four such prism-lights brought together.

A is the body of the prism-light; B, the receiving side; C C, the prisms thereon; D, the two sides of a corner projection developed inside of the space which otherwise would have been occupied by the body of the prism-light had the corner not been cut away.

I claim—

A prism-light cut away at the corners, said corners provided with a projecting part intermediate between the two faces of the prism-light.

WILLIAM S. MACHARG.
